United States Patent Office

Des. 214,687
Patented July 15, 1969

214,687

COIN CHUTE OR THE LIKE

Robert K. Unter, Rockford, Ill., assignor to Keystone Consolidated Industries, Inc., a corporation of Delaware

Filed July 18, 1968, Ser. No. 12,822

Term of patent 14 years

Int. Cl. D20—01

U.S. Cl. D52—3

FIG. 1.

FIG. 2.

FIG. 3.

FIG. 4.

FIG. 5.

FIGURE 1 is a perspective view of a coin chute or the like, embodying my new design;

FIG. 2 is a top plan view thereof;

FIG. 3 is a front elevational view thereof;

FIG. 4 is a side elevational view thereof; and

FIG. 5 is a bottom plan view thereof.

I claim:

The ornamental design for a coin chute or the like, substantially as shown.
